(57) **CLAIM**

The ornamental design for an upper bumper and sleep platform of a bassinet, as shown and described.

DESCRIPTION

FIG. 1 is a perspective view of the upper bumper and sleep platform of a bassinet.

FIG. 2 is a front side plan view of FIG. 1.

FIG. 3 is a rear side plan view of FIG. 1.

FIG. 4 is a top plan view of FIG. 1.

FIG. 5 is a bottom plan view of FIG. 1.

FIG. 6 is a left side plan view of FIG. 1; and,
FIG. 7 is a right side plan view of FIG. 1.

The broken lines in the drawings are for illustrative purposes only and form no part of the claimed design.

1 Claim, 4 Drawing Sheets
